UNITED STATES PATENT OFFICE.

FRANK M. MACKIN, OF BALTIMORE, MARYLAND.

DESIGN FOR A WATER-SUPPLY FIXTURE.

SPECIFICATION forming part of Design No. 25,458, dated May 5, 1896.

Application filed January 23, 1896. Serial No. 576,598. Term of patent 14 years.

To all whom it may concern:

Be it known that I, FRANK M. MACKIN, a citizen of the United States, residing at Baltimore, in the State of Maryland, have invented a novel Design for Double Bath-Cocks; and I do hereby declare the following to be a full, clear, and exact description of the invention, such as will enable others skilled in the art to which it appertains to make and use 10 the same.

This invention has relation to designs for water-supply fixtures for bath-tubs, basins, &c.; and it consists in the novel pattern or shape of the body of the fixture.

15 In the accompanying drawings, Figure 1 is an under side view of the fixture embodying my design, and Fig. 2 is a top view of the same.

The fixture which embodies my design is a 20 double bath-cock and consists of the two cock

bodies or sections A A, cylindrical or approximately so above and below their middle parts A' A' and bulbed or bellied at such middle parts. The sections A A are joined together by a section B, which is of curvilinear contour, its surface merging on unbroken lines into the surface of the sections A A. The section B is at its middle part formed with a rounded bulbous enlargement C and with a cylindrical branch or extension D at right 25 angles to the axis of the section B.

What I claim is—

The design for a water-supply fixture substantially as herein shown and described.

In testimony whereof I affix my signature 35 in presence of two witnesses.

FRANK M. MACKIN.
